WILLIAM BETTS, OF WHARF ROAD, ENGLAND.

Letters Patent No. 71,124, dated November 19, 1867.

IMPROVED METALLIC CAPSULES FOR BOTTLES.

The Schedule referred to in these Letters Patent and making part of the same.

TO ALL WHOM IT MAY CONCERN:

Be it known that I, WILLIAM BETTS, of Wharf Road, Middlesex county, England, have invented an Improvement in Metallic Capsules for Bottles, etc.; and I do hereby declare the following to be a full, clear, and exact description of the same.

This invention relates to those capsules which may be described as "trade-mark capsules," and which are intended to prevent fraud by affording a guarantee of the genuineness of the contents of the bottle covered by such a capsule, and by preventing the re-use of the name of the firm or their trade-mark, as, according to this invention, the capsule itself serves the purpose of a label, which is not only clearly visible from the side of the bottle, but must necessarily be destroyed by the very act of opening the bottle.

In order to enable others to make and apply my invention, I will now proceed to describe the manner of constructing the same, reference being had to the accompanying drawing, which forms a part of this specification, and in which—

Figure 1 is a sectional view of my improved capsule for bottles, etc., and

Figure 2 a view showing the capsule applied to the neck of a bottle.

A is a capsule, of lead, tin, or other malleable metal, which, in the present instance, is of the form shown in the drawing. Upon any suitable part or parts of the body of the capsule I produce, by the aid of type or surface printing and gold-leaf or other foil or metallic powder, the name of the firm, with or without a special trade-mark or ornamentation.

One mode of carrying out this invention consists in taking ordinary type or printing surfaces corresponding to the design to be printed on the capsule, and printing the same on the capsule in gold-size, or other suitable adhesive material, after which I apply gold, silver, or other metal leaf or foil, after the manner of ordinary gilding; or powdered metal or pigments may be applied over the size, and the superfluous powder or leaf then removed, when the name or trade-mark will be clearly visible on the capsule; or I take type or a printing-block, made the reverse to ordinary type, and I apply gold-size, or other suitable adhesive preparation, to such printing surface. I then press thereon a sheet of foil, and from this sheet I transfer the impression to the side of the capsule by rubbing or pressing the foil, the flexibility or pliability of the foil facilitating the transferring of the size to the curved surface of the capsule. The gold or other metallic foil, or powder or powdered pigment, is then to be applied to the capsule, when the name or device will appear clearly thereon; or, in lieu of metallic foil or powder, any suitable printing-ink, colored or not, may be employed; or the name or trade-mark may be produced by a stencilling process; or the letters and trade-mark may be stopped out of the body of the capsule, when the latter is colored, so as to show the name and design in plain metal, whilst the rest of the capsule is colored. These names and trade-marks may be produced, if desired, in two or more colors, by successive printings, whereby the effect of multicolored trade-marks will be obtained. In some cases the name and trade-mark, or name or trade-mark, may be embossed or stamped on the body or side of the capsule.

Although this mode of producing trade-mark capsules is more particularly applicable to the long capsules employed in the champagne trade, it may obviously be employed for short capsules. In all cases where folds or overlaps are formed down the sides of the capsule, in applying them to a bottle-neck, care should be taken that such folds or overlaps come, as nearly as practicable, equidistant on each side of the device produced on the body of the capsule, whereby a neater appearance will be obtained, and all interference with the words or design on the sides of the capsule will be obviated.

I claim as my invention, and desire to secure by Letters Patent—

A metallic capsule, constructed for application to the neck of a bottle, as described, and on which a trade-mark or title is stamped or otherwise permanently imprinted, for the purpose specified.

In testimony whereof I have signed my name to this specification in the presence of two subscribing witnesses.

W. BETTS.
